ATTORNEYS

UNITED STATES PATENT OFFICE.

JEANNE LEEMAN, OF SAN FRANCISCO, CALIFORNIA.

BRASSIÈRE.

1,205,758.

Specification of Letters Patent.

Patented Nov. 21, 1916.

Application filed March 21, 1916. Serial No. 85,582.

To all whom it may concern:

Be it known that I, JEANNE LEEMAN, a citizen of the United States, and a resident of San Francisco, in the county of San Francisco and State of California, have invented a new and useful Improvement in Brassières, of which the following is a specification.

My invention is an improvement in brassières, and the invention has for its object to provide a device of the character specified, which while affording an effective support will be easily adjusted, comfortable in use, and easily removed, and will avoid pressure upon the vital organs of the body.

A further object of the invention is to provide a brassière that can be worn with or without a corset, even during sleep with comfort, and wherein a special manner of attachment is provided at the back.

In the drawings: Figure 1 is a perspective view from the front of the improvement in use, Fig. 2 is a similar view from the rear, and Fig. 3 is a front view of the improvement detached.

In the present embodiment of the invention, a back is provided of fabric material, consisting in the present instance of similar sections 1, connected at their adjacent ends 30 by a double row of stitching 2, and the upper edge of each of the said sections inclines downwardly toward its outer end in order to fit beneath the arms of the wearer.

Sides or front sections 3 are connected 35 with the outer ends of the back sections, each of the side or front sections being connected to the adjacent back section by a double row of stitching 4. A tab 5 is connected with the upper edge of each back section near its connection with the other section, and each tab has connected therewith a shoulder strap 6, each strap having one end permanently connected with the tab.

A bust pocket 7 is connected with the 45 outer end of each of the side sections 3 by means of stitching, each bust pocket being of netting and each of the pockets is provided with a tab 8 at its upper side for connection with the front end of the adjacent shoulder strap 6. The pockets are substantially circular in outline but each pocket is provided with a straight edge at that side adjacent to the other pocket. At this straight edge one of the pockets is provided with a series of buttons 9, and the straight edge of 55 the other pocket is provided with button

holes for engaging the buttons to fasten the brassière in center of front.

The material of the pockets is preferably a coarse mesh net in order that there may be some elasticity and ventilation to prevent injury and discomfort. Each pocket is provided also with a straight edge at its lower side at right angles to the straight edges having the button holes and buttons, and a strip 10 of elastic is connected with each pocket at this point. Each of the strips 9 is passed through loops formed in the material of the pocket and the ends of the strips are connected with the pockets.

In order to hold the support in its proper position, straps 11 are connected with the back sections 1, each section having one strap connected with the lower edge thereof at a point near its connection with the other section. The straps are so shaped that they will fit about the body of the wearer passing forwardly and downwardly around the body, and each of the said straps is provided with tabs or cords 12, for engaging hose supporters indicated at 13.

It will be evident from the description that no rigid or unyielding material of any character, as for instance, bones or stays, is used with the improved support, all parts 85 thereof being of fabric material and being yielding and flexible. The bust pockets which may be of any suitable or desired material, are made in any desired size, and the arrangement of the elastic strips 10 prevents the bust from slipping down. All of the support proper is above the diaphragm 90 so that there is no pressure upon the abdomen, and since the support is not necessarily tight, there is no injurious pressure 95 upon the chest.

For the use of slender persons the strips 10 will be narrow, while for fleshy persons the strips will be of greater width and less yielding. For the last-named class the material of the pockets may be also firmer, and it will be obvious that with slender persons the pockets may be padded, if desired. The straps 11 pass above the hip and in addition to their function of preventing displacement of the support, support the hose.

It will be evident from an inspection of Figs. 1 and 2, that the pockets are shaped like the bust and they are preferably knitted in order to fit smoothly, easily, and comfortably.

The brassière being entirely without stays

or bones can be washed with the same facility as any other undergarment and it may be made of any kind of material that is soft or firm. For stout people it can be made 5 with a strap below the bust in order to prevent sagging and for slender people it may be padded.

I claim: —

1. A brassière of the character specified 10 comprising a band adapted to fit about the back and beneath the arms, having at each end a pocket and a shoulder strap for each pocket and connected at one end to the pocket and at the other to the band and 15 adapted to pass over the shoulders, and hose supporting straps connected with the rear of the band and shaped to extend forwardly and downwardly above the hip bones to

connect with the hose at the front, the pockets having interengaging means for connecting them together and an elastic band beneath each pocket for the purpose specified. 20

2. A brassière of the character specified comprising a band adapted to fit about the back and beneath the arms and to connect at 25 the front, and having shoulder straps and hose supporting straps connected to the rear of the band and shaped to extend forwardly and downwardly and to connect with the hose at the front whereby to exert downward pressure at the rear and upward pressure at the front of the band. 30

JEANNE LEEMAN.
